UNITED STATES PATENT OFFICE.

GEORGE W. WRIGHT, OF SALEM, OHIO.

IMPROVEMENT IN ELASTIC BOSOM-HOLDERS.

Specification forming part of Letters Patent No. 128,994, dated July 16, 1872.

SPECIFICATION.

To all whom it may concern:

Be it known that I, GEORGE W. WRIGHT, of Salem, Columbiana county, in the State of Ohio, have invented a new, useful, and Improved Elastic Shirt-Front or Bosom-Holder; and I hereby declare the following to be a full and exact description thereof, reference being had to the accompanying drawing forming part of this specification.

The nature or essence of my invention consists in the particular construction, combination, and arrangement of devices, forming the improved elastic shirt-front or bosom-holder, described in the following specification, and represented in the accompanying drawing, which shows the improved holder as applied to the person of the wearer.

In the above-mentioned drawing, A is a shirt-front or bosom applied to the bust of the man B, which front, A, has two buttons, C, fastened to each vertical edge of the front

for the loops D D to button on, as shown in the drawing.

The bifurcated ends D D are joined in some convenient manner to the ends of the strap of elastic webbing E, which is shown by dotted lines, passing across the back of the man B, which strap of webbing E is provided with a buckle, F, to adjust it with proper elasticity to persons of various sizes, and also to fronts or bosoms of different widths.

This invention holds the shirt-front smooth and free from wrinkles near the body, and, being elastic, it allows free motion to the body without inconvenience to the wearer.

I claim—

As a new article of manufacture, the elastic, bifurcated, adjustable, and detachable shirt-bosom holder, as shown and described.

GEORGE W. WRIGHT.
